LOG LOADER

Robert Charles Symons, Ottawa, Ontario, Canada, assignor to Timberland Equipment, Inc., New York, N. Y., a corporation of New York

Application February 3, 1948, Serial No. 5,914

15 Claims. (Cl. 214—77)

1

This invention relates to log loading equipment or the like, and more in particular to a log loading device which is mounted onto a truck or the like and is adapted to lift logs from the ground onto a bed or deck and which utilizes power from a motor such as the internal combustion engine of the truck.

An object of this invention is to provide an improved log loader which is of simplified and yet sturdy construction and which is efficient and dependable in operation. Another object is to provide an improved gear reduction and drive arrangement. Another object is to provide an improved winch or windlass. A further object is to provide apparatus of the above character which is adaptable for uses under a wide variety of conditions. A still further object is to provide apparatus of the above character which is inexpensive to manufacture, maintain, and operate. These and other objects will be in part obvious, and in part pointed out below.

The invention accordingly consists in the features of construction, combinations of elements, and arrangements of parts as will be exemplified in the structure to be hereinafter described and the scope of the application of which will be indicated in the following claims.

In the drawings:

Figure 1 is a perspective view of one embodiment of the invention with parts of the truck structure broken away so as to show more clearly certain of the operating mechanisms;

Figure 2 is a plan view of the arrangement of Figure 1 with parts broken away;

Figure 3 is a fragmentary view of certain of the structure as viewed from 3—3 of Figure 2;

Figure 4 is an end plan view of the gear reduction and clutch assembly of Figure 1;

Figure 5 is a fragmentary perspective view of the brake applying structure of Figure 5; and

Figure 6 is a sectional view on the line 6—6 of Figure 4.

Referring particularly to Figure 1 of the drawings there is shown the rear portion of a truck 2 having an open rack 3 with uprights 4 adapted to hold a load of logs. Mounted on the side of the truck is a loading frame 6 which has two loading arms 8 and a cross-frame structure 10. Each of the main loading arms has a right-angle extension 7 by means of which the loading arm is hinged to the truck rack 3 and a main arm or longitudinal portion 5 which has at its free end a log-receiving portion 9. This log-receiving portion 9 is formed by an upwardly-curved end bracket 11 and an angle-bracket 13 which form

somewhat of a channel within which the logs lie during the log lifting operation. That is, the logs are rolled over the end extensions 9 of the two lifting arms against the angular brackets 13 and the two arms cooperate to provide support for the logs.

Each of the right-angle extensions 7 is formed by a channel 12 and an angle plate 14 welded thereto. A triangular reinforced plate 15 is welded to channel 12 and the adjacent portion of arm 5 and holds these members rigidly together. Each of the loading arms is hinged to the underside of truck rack 3 by its hinge plate 14 which is positioned between a pair of mounting plates 16 and is held by a removably pintle bolt 18 extending through the plates. Plates 16 are welded to an angle bracket 20 bolted to the truck rack and spaced from the edge of the truck rack as shown so that the loading frame is pivoted about an axis positioned directly beneath the truck rack and spaced a substantial distance from the edge of the rack. With this pivot axis thus positioned the loading frame swings from the full line position of Figure 2 wherein the main arms 20 are substantially horizontal to the vertical position shown in broken lines directly at the side of the truck rack.

The lifting frame is raised by means of a cable 22 which is connected to the cable drum 23 of a winch or windlass 24 which is mounted slightly to the right of the center of the truck rack. Cable 22 extends over a pair of pulleys 26 and 28 which are carried by an upright frame 30 formed by a horizontal angle bar 32 and two vertical angle bars 34. Bar 32 carries a pair of downwardly projecting pins 36 which project through holes in ear brackets 38 fixed to the truck rack. The upright frame is reinforced by a pair of plates 40 and the entire assembly is welded together so as to form a light-weight rigid construction. Angle bars 34 carry U-shaped cable guards 42 adjacent the pulleys which prevent the cable from slipping off the pulleys. Frame 30 is held in the upright position shown by a chain 44 connected at one end through a clevis 46 to a bracket 48 held by bolts 47 to the truck frame, and (see Figure 3) connected at the other end through a key hole and slot 49 in one of angle bars 34.

Cable 22 is attached to the loading frame 6 by a loop on the end of the cable which is received by a hook 50 (see also Figure 3) welded to the center of the cross-frame structure 10. The cable extends from the lifting frame over the top of pulley 26 (Figure 2) and thence downwardly and

beneath pulley 28 and to the left to drum 23 (see Figure 6). The end of the cable is connected to the drum by a pair of U-clamps 52 (only one of which is shown) the ends of which project through holes in an end flange on the drum and are held by nuts 54. Thus with the lifting frame in the full line position of Figure 2 the turning of drum 23 winds the cable onto the drum and swings the lifting frame to the upright position shown in broken lines.

As indicated above, drum 23 is part of a winch or windlass 24 which is driven from the truck motor and which includes a gear and brake assembly which is somewhat of the planetary gear type and which acts as a clutch. The arrangement is such that when the brake is released drum 23 remains stationary, and when the brake is applied this drum is rotated. Drum 23 includes a pair of cylindrical end flanges 53 and 55, and a cylindrical member 57 upon which the cable is wound; the drum members are welded together, and in turn welded to a shaft 56. Shaft 56 is supported at the right by a bracket 58 having a bearing 65, and at the left by a bracket 60 having a bearing 67. At the left end of shaft 56 and in alignment therewith is a shell 62 which is mounted at the right in bracket 60 through a mounting sleeve 66 welded to the shell and a bearing 88. The bearing sleeve has a radial groove 69 into which a correspondingly shaped ridge on bearing 68 fits so as to hold the members in alignment, and sleeve 66 and bearing 68 surround bearing 88 and shaft 56, thus to provide concentric support for shell 62 and the shaft.

Shell 62 is formed by two disc members or side walls 61 and 63, and a cylindrical member 59. Member 61 is welded at its periphery to member 59 and member 63 is clamped to member 59 with an oil tight seal by a plurality of bolts 65. Shell 62 is supported at the left by a mounting sleeve 72 welded to the shell and journaled by a bearing 74 in a bracket 64. Brackets 58, 60 and 64 are supported at the sides of the winch by a pair of angle bars (see also Figure 4) 73 and 75. Journaled within mounting sleeve 72 in alignment with shaft 56 is a drive shaft 78 which has a sleeve bearing 76. At the left-hand end of mounting sleeve 72 there is an oil seal 77, and at the right-hand end of mounting sleeve 66 is a similar oil seal 79.

The right-hand end of drive shaft 78 projects into shell 62 and has integral with it a gear 80, and the adjacent end of shaft 56 has keyed to it a gear 86. The adjacent ends of shafts 78 and 56 are held in spaced relationship by a washer 84 which is held in place by an extension 87 on the end of shaft 56, and there is a cylindrical recess in the adjacent end of shaft 78 which avoids direct contact between the ends of the shafts. At the left of gear 80 is a washer 87, and at the right of gear 86 is a washer 88', and these washers hold the gears from contact with the sides of the shell.

As shown in the upper portion of Figure 6, shell 62 also encloses a pair of gears 90 and 92 which mesh respectively with gears 86 and 80. Gear 90 has a cylindrical extension 91 upon which gear 92 is keyed and the two gears are mounted through a sleeve bearing 93 upon a shaft 94 with there being washers 95 and 97 at the ends of the sleeve bearing to hold the gears from the sides of the shell. The right-hand end of shaft 94 projects into an opening 99 in member 63 of the shell and this provides a snug support for the shaft. A similar snug support is provided for

the left-hand end of shaft by an opening 100 in member 61 of the shell. The left-hand end of shaft 94 projects from the shell and has an integral flange 96 which is clamped to member 61 with an oil-tight seal by a plurality of stud bolts 98. At the right-hand end of shaft 94, opening 99 is closed by a sealing disc 102 over which a cover plate 104 is held by stud bolts 103.

Shell 62 provides an oil-tight casting for the gears, and at the same time forms with the gears a gear-reduction and clutch assembly. Thus, if the shell is held stationary, the rotation of shaft 78 is transmitted through gears 80, 92, 90 and 86 to shaft 56 with there being approximately a six-to-one reduction in the speed of rotation. And, if shell 62 is permitted to rotate and shaft 56 resists rotation, then the rotation of shaft 78 causes gear 90 to traverse the periphery of gear 86 and this causes shell 62 to rotate. As indicated above, a brake is provided so that shell 62 may be stopped as desired; therefore, when the brake is released the shell rotates freely with the result that drum 23 does not turn, but when the brake is applied the rotation of the shell is stopped and then drum 23 is rotated by a direct gear drive.

The brake is formed by a brake band 110 having a brake lining 112 which engages the cylindrical braking surface of the shell which is the outer surface 111 of member 59. As shown best in Figure 5, brake band 110 is fixed at one end to the supporting angle bar 75 and at the other end to a draw rod 116. Draw rod 116 is threaded at its right-hand end and projects through a diametrical hole in a cylindrical operating pin 118. A pair of sleeves 120 and 122 are held into engagement with the opposite sides of pin 118 by nuts 124 threaded onto rod 116. Pin 118 is rockably carried (see also Figure 5) by a pair of rectangular operating blocks 126 which have a pin 128 projecting through holes in their upper ends; the blocks are clamped to the pin by bolts 127 and the pin is rockably mounted in a pair of fixed brackets 130. Welded to one end of pin 128 is a brake-applying lever 132 which is normally biased downwardly (clockwise in Figure 4) by a coil spring 134 one end of which engages the lever and the other end of which engages angle bar 75. Thus a brake-applying crank is formed by blocks 126, pin 128, and lever 132, and spring 134 normally acts through this crank to urge rod 116 to the left (Figure 5) so as to release the brake from shell 62. The brake is applied by lifting arm 132 so as to swing the arm counter clockwise (Figure 5) thus to pull rod 116 to the right; this action tightens brake band 110 upon the shell and tends to prevent rotation of the shell.

Lever 132 may be raised to apply the brake by pulling a cable 136 which has a loop at its end extending through a hole in lever 132 and which extends upwardly and thence through a pulley 138' in a generally horizontal direction. As shown in Figure 1, cable 136 extends forwardly beneath the truck rack and is connected at the forward end of the rack to a lever 138. Lever 138 is welded to an operating bar 140 which is mounted on the truck rack by three brackets 141 and extends substantially the width of the truck with an operating handle 142 at each of its ends. These handles normally project downwardly and when the operator wants to operate the winch he swings one of the handles forwardly of the truck and this action is transmitted through lever 138 to cable 136 so that (see Figures 4 and 5) the brake-applying lever 132 is raised and the brake is applied.

It has been indicated above that power is transmitted to drive shaft 78 of the winch from the truck motor; for this purpose a winch clutch (not shown) is provided at the motor which provides continuous rotation of shaft 78 when the winch clutch is engaged. Drive shaft 78 (see Figure 1) is connected through a universal joint 143 to a shaft 145 which extends forwardly of the truck and is supported by a bracket 147 bolted to the truck frame. Shaft 145 is connected at its forward end through a universal joint 149 to a shaft 151 which is in turn connected to the winch clutch referred to above. During the log loading operation it is desirable to provide for control of the truck motor by the operator. Accordingly, adjacent rod 148 is a similar rod 144 which is rockably mounted on the truck frame by a pair of brackets 146 and which has at each end a control handle 148. Near the center of rod 144 is a lever 150 to which a throttle control rod 153 is connected. Thus, an operator may engage the winch clutch so as to start the rotation of shafts 151, 145 and 78; then he can control the raising of the loading frame 6 from either side of the truck and he has simultaneous control over the truck motor.

In this embodiment of the invention the lifting action of the winch is stopped automatically at the time the loading frame 6 reaches its fully elevated position. For this purpose the loading frame has a brake-releasing arm 152 (see also Figure 2) which is welded to one side of the loading arm adjacent hinge plate 14. Brake releasing arm 152 is connected through a cable 154 to cable 136 (Figure 1) by a cable clip at 156, and cable 154 extends through a ring loop bracket 158 so that its end runs substantially parallel to cable 136. As the lifting frame moves toward the broken line position of Figure 2, arm 152 swings toward the side of the truck and this pulls cable 154. The length of cable 154 is such that it tightens up and exerts a brake-releasing pull on cable 136 at the time the loading frame approaches the broken line position of Figure 2. That is, as the lifting frame approaches this broken line position, arm 152 pulls cable 154 and the force is exerted through cable 136 to lever 138 so as to swing this lever rearwardly of the truck and so as to move handles 142 back to their rest position. Therefore, the manual force exerted by the operator to apply the brake and operate the winch is overcome so that the brake is released and the winch no longer rotates drum 23; thus, the drum is free to rotate by a pull on cable 22. By this time the log or logs on the loading frame have been thrown or dropped into the truck rack, and the weight and mounting of the loading frame are such that cable 22 is unwound from drum 23 and the loading frame starts to descend immediately to the full line position of Figure 2. In practice it has been found that an operator can load logs very rapidly because he can lift the loading frame at maximum speed and can rely upon the brake-releasing mechanism to stop the lifting operation when the loading frame is fully elevated. The releasing of the brake in this manner may be regulated by adjusting the length of cable 154, and in this way the varied demands of actual use may be met. It has been found that a skilled operator can manipulate control handles 142 and 148 in such a way as to load logs very rapidly and he can even position the logs on the truck rack as he desires by varying the speed of the motor during the lifting movement.

The lifting frame may be mounted on either side of the truck and for this purpose duplicate brackets 16, 38 and 48 are provided for the loading frame 6, the upright frame 30 and chain 44, and a brake-releasing arm 152 is provided on each of the loading arms 8. Thus when the operator wishes to load logs from the opposite side of the truck he first disconnects chain 44 from frame 30 and unhooks cables 22 and 154 from the loading frame 6. The loading frame is then disconnected by removing the two bolts 18 and is carried around to the other side of the truck, and the frame is held with the hinge plates 14 in their respective positions between the plates 16 while bolts 18 are inserted. Lifting frame 30 is then lifted up so as to withdraw pins 36 from brackets 38 and this frame is moved to the other side of the truck and pins 36 are inserted in the other pair of brackets 38; this may be done without removing cable 22 from pulleys 26 and 28. Chain 44 is then connected to the other bracket 48 by taking clevis 46 apart, and the chain is then attached at its free end to frame 30 so as to hold the frame in upright position. Cable 154 is reattached to the arm 152 upon the loading arm which is at that time positioned forwardly of the truck rack. Cable 22 leads off from the bottom of drum 23 and with the arrangement of parts as shown the cable extends freely to pulley 28. Thus minimum effort is involved in adapting the apparatus from operation at one side of the rack to operation at the other side of the rack.

During movement of the truck from one position to another, the lifting frame is held in the upright position shown in broken lines in Figure 2 by a chain 160 on the top of frame 30 which the operator connects (see Figure 3) in a key hole opening 162 in a bracket 160 on the loading frame. In the illustrative embodiment rack 3 is of the so-called "open" type so that cable 22 can extend from drum 23 to pulley 28. However, when the truck rack has a closed bed, pulley 28 is moved to a lower position indicated in broken lines and having its mounting pin positioned in a hole 163. When pulley 28 is in this lower position cable 22 extends beneath the truck rack (Figure 2) as indicated in broken lines. Referring to Figure 6, drum 23 is provided with a cable guard 164 which holds the cable from jumping off the drum. The winch is enclosed in a sheet metal casing which has been generally omitted to show the working parts.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a log loader of the type which may be mounted on a carrying rack or the like, the combination of, a rigid unitary loading frame assembly which is swingably mounted to be elevated from a horizontal log-receiving position wherein it is adapted to receive logs beneath the level of the rack to a substantially vertical log-discharging position wherein it deposits the logs onto the rack, a power unit operatively connected to said loading frame and adapted to elevate the loading frame, a controller to control said power unit, and an auxiliary controller operatively related to said loading frame to be operated by the arrival of the loading frame to

its elevated position and effective to render the power unit inoperative.

2. In a log loader of the character described, a loading frame comprising, a pair of parallel arms which are adapted to swing from a substantially horizontal position wherein the log-receiving end of the arms receives logs to a substantially vertical position wherein the log-receiving end of the arms is elevated above the level of a rack thereby to lift logs from the ground onto the rack, and a pair of pivot members respectively connecting said loading arms to the rack along an axis which is spaced substantially from the adjacent edge of the rack and substantially at the level thereof, said pivot members projecting downwardly from said axis when said arms are in said substantially horizontal position.

3. In apparatus of the character described, the combination of, a rack which is adapted to have logs loaded thereon, a loading frame having a main longitudinal portion and a transverse portion, pivot means connected to said longitudinal portion and connecting said loading frame to the underside of said rack along a pivot axis spaced substantially from the side edge of the rack, said main longitudinal portion being adapted to swing about said pivot axis between a horizontal position and a vertical position at the side of the rack, a cable and pulley assembly which is adapted to lift said main longitudinal portion of the loading frame from its horizontal position to its vertical position, a winch which is adapted to wind up said cable thereby to perform the above-mentioned lifting operation, an operating member which is moved to render said winch operative, and releasing means attached to said loading frame and adapted to render said winch ineffective when said main longitudinal portion of the loading frame reaches its vertical position.

4. In apparatus of the character described, the combination of, a rack which is adapted to have logs loaded thereon, a loading frame having a main longitudinal portion and a transverse portion, pivot means connected to said transverse portion and connecting said loading frame to the underside of said rack along a pivot axis spaced substantially from the side edge of the rack and at substantially the level thereof, said main longitudinal portion being adapted to swing about said pivot axis between a horizontal position and a vertical position at the side of the rack, a cable and pulley assembly which is adapted to lift said main longitudinal portion of the loading frame from its horizontal position to its vertical position, a winch which is adapted to wind up said cable thereby to perform the above-mentioned lifting operation, and an operating member which is moved to stop the winding up of the cable on said winch.

5. In apparatus of the character described, the combination of, a rack which is adapted to have logs loaded thereon, a loading frame having a main longitudinal portion and a transverse portion, pivot means connected to said transverse portion and connecting said loading frame to the underside of said rack along a pivot axis spaced substantially from the side edge of the rack, said main longitudinal portion being adapted to swing about said pivot axis between a horizontal position and a vertical position at the side of the rack, a cable and pulley assembly which is adapted to lift said main longitudinal portion of the loading frame from its horizontal position to its vertical position, and a winch

having its winding axis substantially parallel to said pivot and adapted to wind up said cable thereby to perform the above-mentioned lifting operation.

6. In a log loader of the type which may be mounted on a truck or the like, the combination of, bracket means adapted to be mounted along the underside of the truck rack and providing a pivot along a pivot axis substantially spaced from the adjacent edge of the truck rack, a loading frame comprising a pair of loading arms each of which has a right-angle portion pivoted at one end to said pivot means and adapted to swing between a substantially vertical position directly beneath said pivot axis and a substantially horizontal position along the underside of the truck rack adjacent said edge, each of said loading arms also including a longitudinal member rigidly connected at one end to said right-angle portion and adapted to swing with said right-angle portion from a horizontal position at a substantially lower level than the truck rack to a vertical position at the side of the truck rack, an upright frame mounted on the edge of the truck rack substantially equal distances from the two loading arms and projecting upwardly therefrom and having vertical pins projecting downwardly through retaining recesses at the level of the truck rack, and a pulley mounted in the top of said upright frame and adapted to carry a cable or the like for elevating said loading frame.

7. In a log loader of the type which may be mounted on a truck or the like, the combination of, bracket means adapted to be mounted along the underside of the truck rack and providing a pivot along a pivot axis spaced a predetermined distance from the adjacent edge of the truck rack which predetermined distance is substantially greater than the distance which said axis is below the level of the truck rack, and a loading frame comprising a pair of loading arms each of which has a right-angle portion pivoted at one end to said pivot means and of a length substantially equal to said predetermined distance and adapted to swing between a substantially vertical position directly beneath said pivot axis and a substantially horizontal position along the underside of the truck rack adjacent said edge, each of said loading arms also including a longitudinal member rigidly connected at one end to said right-angle portion and adapted to swing with said right-angle portion from a horizontal position at a substantially lower level than the truck rack to a vertical position at the side of the truck rack.

8. In a log loader of the character described, a loading frame comprising, a pair of loading arms each of which comprises an elongated arm member and a right-angle member connected at one end to one end of said arm member with the right-angle member being adapted to provide at its end opposite the arm member a pivotal mounting whereby the arm member may swing about a pivot substantially above the level of the ground and move between a substantially horizontal position and a substantially vertical position.

9. In apparatus of the character described, a winch comprising, a drum which is adapted to have a cable or the like wound thereon, a driven shaft connected to said drum and providing a mounting means therefor, a substantially cylindrical shell having one end of said driven shaft projecting into one side thereof in coaxial alignment therewith, a drive shaft projecting into the

other side of said shell in coaxial alignment therewith, a plurality of gears within said shell providing a gear reduction train connecting said shafts and including a pair of gears rotatably mounted on an axis parallel to the axis of said shell and displaced therefrom whereby the rotation of said drive shaft exerts a moment tending to rotate said shell and said driven shaft is not rotated if said shell is permitted to rotate freely, and a brake which may be operated to prevent the rotation of said shell.

10. Apparatus as described in claim 3 wherein said winch includes, a rotatable shell which presents a cylindrical braking surface and has axial openings in its side walls, a pair of shafts positioned coaxially with their ends in said openings, one of said shafts being a driving shaft and the other being a driven shaft, a pair of gears fixed respectively to the adjacent ends of said shafts within said shell, and gear means within said shell mounted on an axis which is fixed with respect to said braking surface, said gear means providing a driving gear connection between said gears.

11. Apparatus as described in claim 10 wherein said gears are of different sizes and said gear means comprises a rigid gear assembly formed by gears of different sizes and meshing respectively with said pair of gears, and wherein said apparatus includes a brake extending around said braking surface and presenting a mating surface, and means urging said brake into braking relationship with said braking surface.

12. In apparatus of the type described which may be mounted on a rack, the combination of, bracket means adapted to be mounted on the rack and provide a pivot along a pivot axis substantially spaced from the adjacent edge of the rack, a loading frame which has a right-angle portion adapted to be pivoted at one end to said pivot means and thus being mounted to swing between a substantially vertical position directly beneath the pivot axis and a horizontal position along the underside of the rack adjacent said edge, said loading frame also including a longitudinal portion rigidly connected at one end to said right-angle portion and adapted to swing with said right-angle position from a horizontal position at a substantially lower level than the rack to a vertical position at the side of the rack, an upright frame adapted to be mounted on said edge of the rack substantially centrally of said loading frame and projecting upwardly therefrom, and a pulley mounted on the top of said upright frame and adapted to carry a cable or the like for elevating said loading frame.

13. In apparatus of the character described for use in loading logs or the like onto a rack which has a space for the logs which is substantially greater in longitudinal dimension than in width, a loading frame having a main longitudinal portion and a transverse portion, pivot means for connecting said main longitudinal portion to the underside of the rack whereby the loading frame is pivotally mounted on an axis which extends parallel to the longitudinal dimension of the rack with the main longitudinal portion being adapted to swing about said pivot axis between

a horizontal position wherein it projects outwardly from the side of the rack and a vertical position wherein it projects upwardly at the side of the rack, a cable and pulley assembly adapted to lift said loading frame from a rest position to its elevated position wherein said main longitudinal portion is in its vertical position, winch means to wind said cable thereby to perform the above-mentioned lifting operation, and control means for said winch means comprising an operating lever which is swung from a rest position to render said winch means operative to wind up the cable and releasing means which comprises a cable and pulley means with the cable attached at one end to the loading frame whereby it is pulled during the elevating of the loading frame and having its other end connected to said operating lever and to transmit the movement of the loading frame to the operating lever to move the same to said rest position.

14. Apparatus as described in claim 13 wherein said winch means comprises, mounting means including three bearings positioned in axial alignment and spaced from one another, a first shaft 25 rotatably mounted in two of said bearings and having a free end projecting toward the other bearing, a second shaft rotatably mounted in the other of said bearings and having a free end projecting toward said free end of said first shaft, a rotatable shell enclosing the adjacent ends of said shafts and rotatably mounted with respect to said shafts, means interengaging said shafts and said shell, means integral with said shell and presenting a braking surface, brake 30 means which is adapted to engage said braking surface and resist rotation of said shell, and reel means mounted on said first shaft between its bearings and adapted to have the cable wound thereon which is attached to said loading frame, 35 said brake means being normally disengaged but being engaged when said operating lever is swung from said rest position.

15. Apparatus as described in claim 14 wherein said brake means includes a band brake and 45 spring means to release said band brake, and a lever forming part of said control means and adapted when swung to act to overcome said spring means and tighten said band brake.

ROBERT CHARLES SYMONS.
